Figure 1 is a perspective view of a baseboard register embodying my new design.

Figure 2 is a front elevational view of the register.

Figure 3 is a top plan view of the register.

Figure 4 is a bottom plan view of the register.

Figure 5 is an end view of the register.

The rear wall of the register is plain and both ends have substantially the same appearance.

I claim:

The ornamental design for a baseboard register, substantially as shown and described.
